DESIGN FOR A SEPARABLE BROOCH PIN

Christian Arpad Jakobb, Bayside, N. Y.

Application June 12, 1941, Serial No. 101,426

Term of patent 3½ years

To all whom it may concern:

Be it known that I, Christian Arpad Jakobb, a citizen of the United States of America, residing in Bayside, county of Queens, and State of New York, have invented a new, original and ornamental Design for a Separable Brooch Pin, of which the following is a specification, reference being had to the accompanying drawing, forming part thereof, wherein,

Figure 1 is a front elevational view of a separable brooch pin showing my new design.

Figure 2 is a rear elevational view thereof.
Figure 3 is a side elevational view thereof, and
Figure 4 is a front elevational view of the
separable elements apart.

I claim:

The ornamental design for a separable brooch
pin, substantially as shown.

CHRISTIAN ARPAD JAKOBB.
